UNITED STATES PATENT OFFICE.

FRANCIS JOSEPH REILLY, OF NEW YORK, N. Y., ASSIGNEE TO CHARLES S. PALMER AND DEAN PALMER, BOTH OF SARANAC LAKE, NEW YORK.

PENCIL-SHARPENER CLIP.

1,255,932.

Specification of Letters Patent. Patented Feb. 12, 1918.

Application filed November 16, 1916. Serial No. 131,665.

To all whom it may concern:

Be it known that I, FRANCIS J. REILLY, a subject of the King of Great Britain and a resident of the city of New York, borough 5 of Manhattan, in the county and State of New York, have invented a new and improved Pencil-Sharpener Clip, of which the following is a full, clear, and exact description.

10. This invention relates to pencil sharpening devices and particularly to an improved combination clip and sharpening device.

The object in view is to provide a clip and sharpening device especially adapted 15 for sharpening the lead used in a magazine lead pencil.

Another object in view is to provide a clip for a pencil using a removable lead in which the clip will act in the double capacity 20 of a clip for holding the pencil body in position in the pocket and as a sharpening member for the lead when removed from the pencil body, the sharpener acting as a rounded end for the clip.

25. In the accompanying drawing:—

Figure 1 is a plan view of a pencil with a clip embodying the invention shown applied thereto.

30. Fig. 2 is a perspective view of the clip shown in Fig. 1.

Fig. 3 is an edge view of the lower part or sharpener end of the clip shown in Fig. 2, the same being shown on an enlarged scale.

35. Referring to the accompanying drawing by numerals, 1 indicates the pencil body having the lead 2 held in place by suitable mechanism in the lower end 3 of the body 1, the particular construction of pencil body 40 and mechanism at end 3 not forming any part of the invention. Arranged on the body 1 is a clip 4 which is provided with encircling arms 5 and 6 and a downwardly extending tongue 7 which merges into a

45. sharpener 8. It is evident that the upper part of the clip could be formed in some other way than that shown in the drawing, as for instance, by being formed straight and riveted or secured to the body 1 in some other manner. As far as the present invention is concerned the clip could be made in any suitable shape provided some sort of a clamping tongue 7 is produced merging into a coiled end 8. The extreme end of the

50. tongue 7 before it is formed into coil 8 is

sharpened or provided with a bevel 9 whereby an edge 10 is produced, edge 10 being at an angle so that when the parts are coiled for producing coil 8 a tapering socket will be the result with the edge 10 arranged on 60 an angle for acting on the lead 2 when positioned as shown in dotted lines in Fig. 1.

Whenever the lead 2 becomes dull the same may be removed and placed into the sharpening device, namely, in coil 8, and 65 rotated for a few times, whereupon the edge 10 will act on the lead and produce a point. It will be observed that the coil 8 merges into the body of tongue 7 and produces a rounded contact portion 11 while 70 the coil itself is an enlargement, thereby producing an end to the tongue which will readily slip over the pocket when applying the clip to the pocket.

What I claim is:

75. 1. A clip of the character described, comprising a body formed with encircling portions and a depending resilient arm, said arm having a flat section at the end formed into a conical roll, the end of the conical 80 roll being sharpened, said roll extending transversely of the arm, whereby the roll will act as a lead sharpener and as a guide for the clamping arm.

2. The improved pencil attachment which 85 consists of a pencil engaging portion, and a pocket engaging portion, said pocket engaging portion comprising a metallic shank which is secured to the pencil engaging portion at one end and is provided with a pencil sharpener at the other end, said pencil sharpener being arranged to act as a guide 90 to enable the pocket engaging portion to be guided over the outer edge of a pocket.

3. The improved pencil attachment comprising 95 a band for attachment to a pencil, a spring shank portion connected with the band and adapted to extend alongside of the pencil whereby the device may cooperate with a pencil held therein for attachment to a pocket, and a pencil sharpener on the opposite end of the shank from that to which the band is attached, said pencil sharpener being arranged to act as a guide 100 to enable the pocket engaging portion to be 105 guided over the outer edge of a pocket.

4. The improved pencil attachment which 110 consists of a pencil engaging portion and of a pocket engaging portion, said pocket engaging portion having a shank which is

secured to the pencil engaging portion, and a sharpener secured to said pocket engaging portion which has a hole therein at one side of which is a knife edge and which is arranged to act as a guide to enable the pocket engaging portion to be guided over the outer edge of a pocket.

5. The improved pencil attachment which consists of a pocket engaging portion, and 10 of a pencil engaging portion, said pocket engaging portion comprising a shank and a pencil sharpener, said sharpener consisting of a cone-shaped spiral having a sharpened inner end and arranged to act as a

guide to enable the pocket engaging portion 15 to be guided over the outer edge of a pocket.

6. The improved pencil attachment which consists of a pencil engaging portion and a pocket engaging portion of spring metal secured to said pencil engaging portion at 20 one end and provided at its free end with a lead sharpener, said lead sharpener consisting of a cone-shaped spiral which is sharpened at its inner end to form a knife edge. and arranged to act as a guide to enable the 25 pocket engaging portion to be guided over the outer edge of a pocket.

FRANCIS JOSEPH REILLY.
